UNITED STATES PATENT OFFICE.

CHARLES H. HILL, OF SCHENECTADY, NEW YORK, ASSIGNOR TO GENERAL ELECTRIC COMPANY, A CORPORATION OF NEW YORK.

INTERLOCKING DEVICE FOR CIRCUIT-BREAKERS.

No. 833,210.

Specification of Letters Patent.

Patented Oct. 16, 1906.

Application filed February 3, 1905. Serial No. 243,963.

To all whom it may concern:

Be it known that I, CHARLES H. HILL, a citizen of the United States, residing at Schenectady, county of Schenectady, State 5 of New York, have invented certain new and useful Improvements in Interlocking Devices for Circuit-Breakers, of which the following is a specification.

My invention relates to breakers for electric circuits; and its object is to provide a simple and positive interlock between two circuit-breakers so arranged that the opening of one of the breakers will produce a simultaneous operation of the second, while the second breaker may be free to operate without disturbing the first.

It sometimes happens that it is desirable upon the breaking of one of two circuits that the other circuit should be also broken 20 immediately, while it is of no importance that opening the second circuit should produce an opening of the first. Such a case, for instance, is that of a motor-generator set 25 charging a storage battery. If the motor-circuit is opened from any cause, such as an overload, it is important that the battery should be immediately disconnected from the generator, both to prevent discharge of the battery and also to prevent the generator 30 from operating as a motor supplied from the battery and possibly running away and resulting in damage. On the other hand, breaking the battery-circuit can have no 35 dangerous effect upon the motor-generator set. Consequently, while it is desirable that the breaker in the motor-circuit should produce by its operation a simultaneous operation of the breaker in the battery-circuit, the latter breaker should be free to operate without 40 disturbing the first.

My invention is designed to offer a simple and efficient interlock for such and similar cases; and it consists in the combination, with two circuit-breakers, of a member operated 45 by the movement of one breaker and connections between that member and the tripping device of the second breaker, whereby movement of the member trips the second breaker, while free movement of the tripping 50 device is permitted without producing a corresponding movement of said member.

More specifically stated, my invention consists in the combination of two breakers

and a rod connecting the breakers, of means such as a spring tending to move the rod, 55 means for preventing the movement of the rod as long as one breaker is closed, and a lost-motion connection between the rod and the tripping mechanism of the second breaker such that a movement of the rod trips the 60 second breaker; but the tripping mechanism of the second breaker is free to move without moving the rod.

My invention will best be understood by reference to the accompanying drawings, in 65 which—

Figure 1 shows a front elevation of the two circuit-breakers provided with interlocking means arranged in accordance with my invention. Fig. 2 shows a side elevation 70 of one of the breakers and of the interlocking means. Fig. 3 shows a front elevation of the interlocking means corresponding to Fig. 1 with the parts in the position they assume when the circuit-breakers are tripped. 75 Fig. 4 shows a view looking upward at the interlocking mechanism of Fig. 1. Fig. 5 shows a similar view looking upward at the interlocking mechanism in the position shown in Fig. 3. Fig. 6 is a longitudinal section of the locking device along the axis of the rod D, and Fig. 7 is an end view of the stationary member J.

In Fig. 1, A and B represent two automatic circuit-breakers in separate circuits 85 provided with the tripping devices a and b, respectively. These circuit-breakers and their tripping devices may be of any well-known type, and the details of construction, which form no part of my present invention, 90 need not be described here. The circuit-breaker A carries a stud C, (clearly shown in Fig. 2,) which when the circuit-breaker is closed engages the head of a pin D, which extends through the board and the rear end 95 of which engages one arm of the lever E. This lever, which is clearly shown in Figs. 4 and 5, is provided with a tension-spring F, which tends to move it, so as to press pin D forward. This movement is prevented as 100 long as the circuit-breaker A is closed; but upon the opening of the circuit-breaker the pin D is pushed forward, as shown in Fig. 5, until the projection d engages the bottom of a slot in the stationary member J. Another 105 arm of the lever E is pivotally connected to

the rod G, the farther end of which engages by a pin-and-slot connection an arm H, rigidly secured to the shaft h. The shaft h carries a second arm H' on the front of the board, one end of which when raised engages the tripping mechanism b of circuit-breaker B, as shown in Fig. 1. It is evident that if the rod G be moved toward the left in Fig. 1 the shaft h will be rocked so as to bring the end of arm H' into engagement with the tripping mechanism b, while, on the other hand, owing to the pin-and-slot connection between arm H and rod G, arm H is free to move toward the left a small distance without producing any movement of the rod G. The shaft h carries a third arm H², (shown in Fig. 1,) which is controlled by an underload or no-voltage release-coil I. The particular form of underload release shown consists of the coil I and its armature i, which is normally held raised in the position shown in Fig. 1; but when coil I is deenergized armature i falls, as shown in Fig. 3, bringing the nut i' into engagement with the arm H² and rocking shaft h, as shown. It is this movement which is permitted by the pin-and-slot connection between the arm H and rod G as long as rod G is in the position shown in Figs. 1 and 4.

30 The operation is then as follows: With the parts of the interlocking mechanism in the position shown in Figs. 1, 2, and 4 the circuit-breaker B may be tripped by the rocking of shaft h without moving rod G, and consequently without interfering with circuit-breaker A. On the other hand, if circuit-breaker A is tripped by its own tripping device pin D is free to move forward, and consequently spring F will produce a movement 40 of rod G toward the left, as viewed in Fig. 1, rocking shaft h and tripping circuit-breaker B—that is, the parts will be brought into the position shown in Figs. 3 and 5. If after the breakers have tripped it is desired to close breaker B without again closing breaker A, the pin D may be pushed backward and given a quarter-turn, so as to bring the projection d into engagement with the shoulder j on the stationary member J. The projection d is held by the tension of the spring against the end of the member J and between the shoulder j and the pin k. The pin D is thereby prevented from moving forward into the position shown in Fig. 5 and 50 rod G is pushed toward the right, as viewed in that figure, and held there, so as to permit the closing of breaker B without being immediately tripped again by the arm H'. When breaker A is again closed, however, 60 pin D is lifted away from the end of the member J, and the spring then turns the rod D to normal position, in which the projection d is in line with the slot in the member J, and the two breakers are interlocked, as before.

Although I have shown the rod G con-

nected to the underload tripping device of breaker B, my invention is obviously not limited to this particular arrangement. Consequently I do not desire to limit myself to the particular construction and arrangement 70 of parts here shown, but aim in the appended claims to cover all modifications which are within the scope of my invention.

What I claim as new, and desire to secure by Letters Patent of the United States, is— 75

1. In combination, two automatic circuit-breakers, a movable member operated by the opening of one circuit-breaker, and a lost-motion connection between said member and the tripping mechanism of the second circuit-breaker.

2. In combination, two automatic circuit-breakers, a movable member operated by the opening of one circuit-breaker, and a loose yet positive connection between said member and the tripping mechanism of the second circuit-breaker, whereby a movement of said member operates said tripping mechanism, but a movement of said mechanism is permitted without movement of said member. 85

3. In combination, two automatic circuit-breakers, a spring-actuated member connecting said breakers, connections between one of said breakers and said member whereby movement of said member is prevented when 95 said breaker is closed, and connections between said member and the tripping mechanism of the second breaker.

4. In combination, two automatic circuit-breakers, a movable rod connecting said breakers, a spring acting upon said rod, connections between said rod and one breaker whereby said rod is moved against the pressure of said spring when said breaker is closed, and connections between said rod and the 105 tripping mechanism of the second breaker whereby said breaker is tripped when said rod is released by the opening of the first breaker.

5. In combination, two automatic circuit-breakers, a movable rod connecting said breakers, a spring acting upon said rod, connections between said rod and one breaker whereby said rod is moved against the pressure of said spring when said breaker is closed, 110 and a lost-motion connection between said rod and the tripping mechanism of the second breaker.

6. In combination, two automatic circuit-breakers, a movable rod connecting said breakers, a spring acting upon said rod, connections between said rod and one breaker whereby said rod is moved against the pressure of said spring when said breaker is closed, 120 connections between said rod and the tripping mechanism of the second breaker whereby said breaker is tripped when said rod is released by the opening of the first breaker, and means for locking said rod in an inoperative position. 130

7. In combination, two automatic circuit-breakers, a movable member operated by the opening of one circuit-breaker, a lost-motion connection between said member and the tripping mechanism of the second circuit-breaker, and means for locking said member in an inoperative position.

8. In combination, two automatic circuit-breakers, a movable member, operative connections between said member and said breakers whereby the opening of one breaker trips the other, and means for locking said member in an inoperative position.

9. In combination, two automatic circuit-breakers, a movable rod loosely yet positively connected to the tripping mechanism of one breaker, a spring tending to move said rod to trip said breaker, and a member engaging said rod and adapted to be engaged by the second breaker when closed to push said rod into an inoperative position.

10. In combination, two automatic circuit-breakers, a movable rod loosely yet positively connected to the tripping mechanism of one breaker, a spring tending to move said rod to trip said breaker, a member engaging said rod and adapted to be engaged by the second breaker when closed to push said rod into an inoperative position, and means for locking said member to hold said rod in said position

regardless of the position of said second breaker.

11. In combination, two automatic circuit-breakers, a movable member, operative connections between said member and said breakers whereby the opening of one breaker trips the other, and means for locking said member in an inoperative position, said locking means being released to permit said movable member to return to operative position when the first-mentioned circuit-breaker is closed.

12. In combination, two automatic circuit-breakers, a movable member, operative connections between said member and said circuit-breaker whereby the opening of one breaker trips the other, a loosely-mounted rod engaging said movable member, and means for locking the said rod in position to hold said movable member in inoperative position, said rod being released when moved endwise by the closing of the first-mentioned circuit-breaker, whereby the movable member is restored to operative position.

In witness whereof I have hereunto set my hand this 1st day of February, 1905.

CHARLES H. HILL.
